DESIGN FOR A CONVERTIBLE CUFF SLIPPER OR SIMILAR ARTICLE

Esther Cadous, Brooklyn, N. Y.

Application April 7, 1938, Serial No. 76,342

Term of patent 7 years

To all whom it may concern:

Be it known that I, Esther Cadous, a citizen of the United States of America, residing in New York city, in the Borough of Brooklyn, county of Kings, and State of New York, have invented a new, original, and ornamental design for a Convertible Cuff Slipper, or Similar Article, of which the following is a specification, reference being had to the accompanying drawing, forming part thereof, wherein,

vertible cuff slipper, or similar article, in a tied position as it would appear when in use, showing my new design; and

Figures 2 and 3 are, respectively, top and bottom plan views in spread-out positions.

I claim:

The ornamental design for a convertible cuff slipper, or similar article, substantially as shown, and described.

ESTHER CADOUS.
